UNITED STATES PATENT OFFICE.

JOHN MORRISON, JR., OF TROY, NEW YORK.

PNEUMATIC BRUSH-FILLING MACHINE.

No. 824,503.

Specification of Letters Patent.

Patented June 26, 1906.

Application filed April 6, 1905. Serial No. 254,237.

To all whom it may concern:

Be it known that I, JOHN MORRISON, Jr., a citizen of the United States, and a resident of Troy, in the county of Rensselaer and State of New York, have invented a new and Improved Pneumatic Brush-Filling Machine, of which the following is a full, clear, and exact description.

My invention relates to brush-filling machines, and more particularly to mechanism for manipulating the bristles by means of air-currents.

Reference is to be had to the accompanying drawings, forming a part of this specification, in which similar characters of reference indicate corresponding parts in all the figures.

Figure 1 is a perspective view of a machine embodying my invention and ready for use. Fig. 2 is an enlarged side elevation, partly broken away, of one of the brush-filling dies and its accompanying parts removed from the table. Fig. 3 is an end elevation, also enlarged, showing the die and its accompanying parts removed from the table. Fig. 4 is a front elevation, partly in section, showing the dies as spaced apart and indicating by arrows the course of the air-currents; and Fig. 5 is a fragmentary plan view of the table 40 with the dies mounted thereupon and spaced apart.

The table is shown at 4 and is provided with supporting-legs 5. A receptacle 6 depends from the table 4 and is connected by an air-conduit 7 with a blower 8, which is propelled by means of a power-belt 9. From the blower 8 another air-conduit 10 leads upward through the table 4, and revolvably mounted upon its upper end is an elbow 12, connected thereto by means of a swivel-joint 11. The elbow terminates in a pyramidal nozzle 13. Immediately back of the table 4 is a box 14, used for purposes hereinafter mentioned. Mounted upon the table are supporting-rails 15, intermediate of which is a comparatively wide slot 4a. A die is shown at 16 and is provided with a concavity 17 and with a number of bristle-holes 18, extending through the die and merging into the cavity. Each bristle-hole 18 terminates in an aperture 19 of frusto-conical shape. The die 16 is provided with dowel-holes 20 and with depending lugs 21 22 of the shape indicated. A coffin 23 is closed at its top by means of a wire sieve 24 and is provided with dowel-pins 25, which pass into the dowel-

holes 20, thereby holding the coffin 23 securely in position upon the die. A bristle-shield 26 is provided with a sloping edge 27 and with a clamp 28, the clamp being integral with the body of the shield. The upper portion of the clamp 28 is provided with folds 29, disposed upon opposite sides of the die 16 and adapted to engage the same so as to secure the bristle-shield 27 directly in position, as indicated in Fig. 3. The lugs 21 serve to prevent the shields from being moved laterally by means of the air-currents or otherwise displaced from any cause.

The operation of my device is as follows: The operator stands in front of the table 4, while the machine is in action. He scatters bristles loosely over the several dies, and the blower 8 being in motion the bristles are drawn downwardly by air-currents and pass through the air-conduit 7 to the blower 8, thence through the air-conduit 10 to the nozzle 13, whence they are forcibly driven downward upon the several screens 24 and also intermediate of the several dies. A great many of the bristles by falling through the screens 24 land upon the die in such position as to stand vertically within the bristle-holes 18, and the dies are thus filled. The operator constantly whisks from the tops of the screens 24 any bristles which may happen to lodge in horizontal position, and such of these bristles as drop endwise through these screens are apt to lodge vertically within the bristle-holes 18. The excess of bristles is constantly whisked off intermediate of the dies into the air-spaces and is again carried through the pneumatic conduits 7 10 and then showered upon the screens 24. The several dies having been filled the operator removes them. He next takes off the coffin 23, carrying the screen 24, and then rests a board or plate upon the upper surface of the die 16 and quickly inverts both the board or the plate and the die. This leaves numerous bunches of bristles protruding through the holes 18 into the concavity 17 of the die. The operator then fills the concavity 17 with plastic material so as to embed the ends of the bristles, removes the member thus formed, and otherwise proceeds with the manufacture of the brush, the several subsequent steps being old and well known. The die forms no part of the brush.

If desired, the several dies can be placed close together, so as to prevent the bristles from entering the hopper 6 to any great ex-

tent, except as fed in by the operator. In this event the bristles are carried around through the conduits and showered upon the screens 24, the excess being whisked off by the 5 operator—say at the edge of the slot 4^a or intermediate of any two or more consecutive dies, as desired. Again, it may be desirable to distribute the bristles by hand upon the screens 24 and to have the machine 10 remove the superfluous bristles to some other point. In order to accomplish this result, the elbow 12 and the hopper 6 are swung around to the position indicated by dotted lines in Fig. 1, the bristles falling into the box 14, 15 whence they may be removed at will by the operator.

It should be understood, of course, that loose bristles may be filled into the brushes by hand, or partially by the aid of mechanism. 20 I consider it desirable, therefore, to have the machine so constructed that it may blow the bristles downward upon the screens 24, where the bristles are fed into the machine by hand, or to draw the bristles downward 25 into the hopper 6 by suction when fed by hand upon the screens 24, or to both blow the bristles downward upon the screen 24 and remove the superfluity by means of suction through the hopper 6, as desired by the operator. I recommend that in all instances 30 the operators stand by the machine with a whisk-broom or analogous member in hand, and that he occasionally assist the machine in case anything should go wrong with the falling bristles.

Having thus described my invention, I claim as new and desire to secure by Letters Patent—

1. In a brush-filling machine, the combination of a die provided with apertures for holding tufts of bristles, a bristle-shield provided with clamps engaging said die, said bristle-shield being supported by said clamps so as to depend from said die, and means for showering bristles upon said die.

2. The combination of a die provided with bristle-holes, a bristle-shield connected with said die and spaced therefrom, said bristle-shield being supported by clamps engaging 50 said die directly, and a screen provided with a portion engaging said die and with members for holding said screen in a predetermined position relatively to said die.

3. The combination of a die to be filled 55 with bristles, a screen spaced apart from said die and stationary in relation thereto, and pneumatic mechanism for showering loose bristles continuously upon said screen.

4. The combination of a receptacle, means for mounting a die thereover, a screen provided with members engaging said die so as to support said screen, a pneumatic conduit connected with said die, a blower connected with said pneumatic conduit, another pneumatic conduit connected with said blower, 65 and means connected with said last-mentioned pneumatic conduit for continuously showering loose bristles upon said screen.

5. The combination of a plurality of stationary dies separated by air-spaces, and 70 pneumatic mechanism for forcibly showering loose bristles upon said dies.

6. In a brush-filling machine, the combination of a die, a bristle-shield connected with said die but spaced apart therefrom, so as to 75 permit an escape of air through said die, and pneumatic mechanism for showering loose bristles continuously upon said die.

7. In a brush-filling machine, the combination of a die, a stationary screen mounted 80 thereover, and pneumatic mechanism for continuously showering loose bristles upon said screen.

8. In a brush-filling machine, the combination of a plurality of dies provided with bristle-holes and separated by air-spaces, and 85 pneumatic mechanism for drawing air and bristles through said dies and also through said air-spaces.

9. In a brush-filling machine, the combination of a die, a stationary screen mounted 90 thereover, a pneumatic conduit connected with said die, a blower connected with said pneumatic conduit, and a second conduit connected with said pneumatic conduit and terminating in the open air for the purpose of 95 showering loose bristles upon said screen and die.

10. The combination of a die to be filled with bristles, a screen spaced apart from said 100 die and stationary in relation thereto, pneumatic mechanism provided with a conduit terminating in the open air at a point disposed adjacent to said die, and means for forcing air through said conduit relatively to said die. 105

11. The combination of a die provided with bristle-holes, a bristle-shield disposed adjacent to said die, and a screen connected with said die for guiding bristles thereinto.

In testimony whereof I have signed my name to this specification in the presence of two subscribing witnesses.

JOHN MORRISON, JR.
